UNITED STATES PATENT OFFICE.

EUGENE A. SAVARY, OF PHOENICIA, NEW YORK.

STAIR-CARPET SUPPORT.

Application filed January 3, 1925. Serial No. 306.

To all whom it may concern:

Be it known that I, EUGENE A. SAVARY, a citizen of the United States, residing at Phoenicia, in the county of Ulster and State of New York, have invented new and useful Improvements in Stair-Carpet Supports, of which the following is a specification.

This invention relates essentially to a device for fastening a carpet to a stairway and it fundamentally comprehends a spring member provided with pointed ends to pierce the carpet and the stair tread.

An object of the invention is to provide a longitudinally compressible flexible fixture made to adjust itself to the variable height of the stair riser.

Another object of the invention is to joint the members together so that they can be readily locked in position to hold the carpet to the riser and treads of the stairway.

The invention resides more particularly in the novel combinations hereinafter described and claimed, reference being made to the accompanying drawing in which:—

Fig. 1 represents a front elevation of a device embodying this invention.

Fig. 2 is a vertical section taken along the line 2 2 of the same.

In the drawing the numeral 5 designates a pair of treads and 6 is a riser connecting the treads of an ordinary stairway. The means for fastening the carpet 7 to the stairway consist of an upper member having a pair of parallel shanks 8 each with a lateral arm 9 extending at right angles from the shank. Each arm is provided with an upwardly projecting pointed end 10 adapted to pass through the carpet and engage the underside of the nosing. The shanks are prevented from spreading by means of a clip 11 arranged below the arms. The lower ends of the shanks have loops 12 and a downwardly depending handle 14 for grasping to manipulate the upper member. As indicated in Fig. 1 the upper member is formed of a single length of resilient steel or brass wire.

The looped ends 12 coact with a transverse bar 15 of a lower fixture member. The bar has downwardly extending spring legs 16 which are curved outwardly so that the legs

can adjust themselves to the maximum variation of a quarter of an inch more or less in the height of the riser. The legs are held together by means of a clip 17 embracing the legs. The lower portion of each leg is bent at right angles to form a pair of lateral arms 18 having pointed ends 19 to pass through the carpet and the tread.

The loop 12 in combination with the bar forms a hinge joint between the two members and when the device is in place the handle is clamped between the humps or jaws 20 formed in the upper portion of the lower legs to prevent the members from being accidentally unlocked. When it is desired to remove the fixture the handle is pulled outwardly thus swinging both members away from the riser and the pointed ends can be forced out of engagement with the tread to release the carpet.

As indicated in Fig. 1, the fixture is positioned between the two treads, the upper pointed ends being made to pierce the carpet bent under the nosing, while the lower pointed ends engage the tread near the lower end of the riser. The fixture being contractile longitudinally will adjust itself to treads of different depths merely by springing it into place.

I claim:—

1. A stair carpet support comprising an upper member made of resilient wire, said member having a pair of shanks each provided with a pointed lateral arm for engagement with the tread of a stairway, the lower portions of the shanks forming loops and a handle depending from the loops; combined with a lower resilient wire member having a pair of legs the upper portion of which forms a transverse bar to hinge the lower member to the loops, and pointed lateral arms extending from the legs for engagement with the tread of a stairway, said legs being adapted to clasp the handle.

2. A stair carpet support comprising an upper member made of resilient wire, said member having a pair of shanks each provided with a pointed lateral arm for engagement with the tread of a stairway, the lower portions of the shanks forming loops and a

handle depending from the loops; combined with a lower resilient wire member having a pair of legs the upper portion of which forms a transverse bar to hinge the lower member to the loops, and pointed lateral arms extending from the legs for engagement with the tread of a stairway, said

legs having inwardly curved portions to provide jaws for clasping the handle therebetween.

In testimony whereof I have hereunto set my hand.

EUGENE A. SAVARY.
